(57) **CLAIM**

The ornamental design for a bottle-to-bottle connector, as shown and described.

DESCRIPTION

FIG. 1 is a front elevation view of a bottle-to-bottle connector showing my new design;

FIG. 2 is a rear elevation view thereof;

FIG. 3 is a left side elevation view thereof;

FIG. 4 is a right side elevation view thereof;

FIG. 5 is a top plan view thereof;

FIG. 6 is a bottom plan view thereof;

FIG. 7 is a top perspective view thereof;

FIG. 8 is a front elevation view thereof showing the bottle-to-bottle connector attached to two bottles transferring contents;

FIG. 9 shows a front elevation view of a second embodiment of my claimed design;

FIG. 10 is a rear elevation view thereof;

FIG. 11 is a left side elevation view thereof;

FIG. 12 is a right side elevation view thereof;

FIG. 13 is a top plan view thereof;

FIG. 14 is a bottom plan view thereof; and,

FIG. 15 is a top perspective view thereof.

The broken lines depicting exemplary bottles in FIG. 8 depicts environmental subject matter only and form no part of the claimed design.

FIGS. 9-15 show the bottle-to-bottle connector with a symbolic break in its height. The appearance of any portion of the article between the break lines forms no part of the claim.
